(57) **CLAIM**

The ornamental design for a brush caddy, as shown and described.

DESCRIPTION

FIG. 1 is a perspective view of a brush caddy showing my new design;

FIG. 2 is a front view thereof, the right side, left side and rear being mirror images thereof;

FIG. 3 is a top view thereof; and,

FIG. 4 is a cross-sectional view taken along line 4—4 of FIG. 2.

The unshaded interior section of the brush caddy shown within the broken line immediately adjacent to the shaded areas of FIG. 4 forms no part of the claimed design.
